P. STELLA

RAIL JOINT

Filed March 10, 1924

Inventor:

Pasquale Stella,

By
Mason, Fenwick, Lawrence, *et alii*

UNITED STATES PATENT OFFICE.

PASQUALE STELLA, OF CHICAGO, ILLINOIS, ASSIGNOR OF ONE-HALF TO CHARLES AMICO, OF CHICAGO, ILLINOIS.

RAIL JOINT.

Application filed March 10, 1924. Serial No. 693,197.

To all whom it may concern:

Be it known that I, PASQUALE STELLA, a citizen of the United States, residing at 1012 Newberry Avenue, Chicago, in the county of Cook and State of Illinois, have invented certain new and useful Improvements in Rail Joints; and I do hereby declare the following to be a full, clear, and exact description of the invention, such as will enable others skilled in the art to which it appertains to make and use the same.

This invention relates to rail joints, and among the objects thereof are to provide a rail joint wherein confronting or meeting ends of railway rails and the angle bars or fish plates may be secured together and in place without the use of screw-threaded bolts and nuts, and in which the rails are connected in a manner to hold them against lateral, tilting or vertical movement and to permit only such longitudinal movement as is required in the expansion and contraction of the rails, while also providing an efficient electric bond, the construction being such that the confronting ends of the rails may be connected after the rails have been brought into engagement, and likewise removed therefrom without necessitating the movement of the rails away from each other. By dispensing with the usual threaded bolts and nuts, likelihood of displacement or of the parts coming loose, is prevented, and accidents thereby avoided.

With the above and other objects in view, the invention consists of certain novel combinations and arrangements of parts as will be hereinafter more particularly set forth and described.

In accompanying drawings,

Fig. 1, is a top plan view showing the confronting ends of two rails connected by the novel rail joint.

Fig. 2, is a cross-sectional view taken on the line 2—2 of Fig. 1.

Fig. 3, is a perspective view of a wedging member employed in connection with the joint.

Fig. 4, is a perspective view of a yoke member employed in connection with the joint and which embraces the angle bars and the wedge member, and

Fig. 5, is a perspective view of one of the angle bars.

Referring to the drawings in detail, in which like reference characters designate

corresponding parts throughout the several views, 6 and 7 represent the ends of two rails which are to be joined in abutting relation at their confronting or meeting ends and which are united by means of angle bars or fish plates 8 and 9, secured to opposite sides of the rails 6 and 7. These angle bars, 8 and 9 are provided with studs 10 suitably formed therewith or secured thereto. As shown, the studs 10 are provided with reduced portions 65 11 entering apertures 12 in the fish plates or angle bars and riveted or headed as shown at 13 in suitable countersunk portions of the apertures to dispose the heads flush with the outer faces of the angle bars and provide a 70 rigid attachment thereof. The studs 10 pass through spaced apertures 14 in the rails 6 and 7 and enter apertures 15 in the angle bars 8 and 9, which apertures 15 are disposed in spaced relation, preferably in alternate 75 relation with respect to the studs 10 and apertures 12 which receive such studs.

The angle bars or fish plates 8 and 9 are securely held to opposite sides of the rails 6 and 7 so that the flanges 16 thereof, rest 80 upon the base flanges 17 of the rails 6 and 7, by means of a yoke member 18 which is provided with a notch 19 in one side wall running transversely through its thickness immediately below the inner end 20, while the 85 opposite inner end 21 is wider than the inner end or face 20, that is, deeper from the top to bottom, and the notch correspondingly omitted. However, an inclined extension or a groove 22 is provided at the side beneath 90 the end or face 21 of the yoke member 18, which continues in an outwardly and downwardly inclined direction from the bottom face 23. A lateral extension or projection 24 is provided at one side of the yoke member 95 with its upper face flush with the bottom face 23, the purpose thereof being to engage the bottom face of the rail and prevent turning or tilting of the yoke and thus to retain it firmly in position when once disposed in place and fastened, as will be hereinafter more fully described.

A wedge member 25 is adapted to cooperate with the yoke member 18 and is tapered toward one end to provide an inclined 105 or wedge face 26, and is provided at the base or bottom with a lateral extension 27 tapered at its widest end to provide an inclined or wedge surface 28. The lateral extension 27 provided at the lower edge of the 110

wedge member 25, is provided with a plurality of spaced vertical apertures 29, preferably arranged in staggered relation as shown.

5 It will be noted that the notch 19 is adapted to receive the lateral extension 27 of the wedge member 25, the purpose of which as will be noted, is to prevent the wedge member from moving in an upward direction 10 within the yoke member 18. It will thus be seen that when the rail joint is assembled, the yoke member 18 is slipped over the rail from the under side thereof by tilting the yoke so that the base or bottom of the rail, 15 forming the flanges, will enter the inclined groove 22 in the yoke member 18, as more particularly shown in Fig. 2 of the drawings in dotted lines. The fish plates or angle bars, are then placed on opposite sides 20 of the rail ends, the studs 10 of the angle bars 8 and 9 entering the apertures 15 of the opposite angle bars or fish plates after passing through the apertures 14 of the confronting rail ends of the rails. After the 25 fish plates or angle bars have been properly located and secured to opposite sides of the rails, the yoke member 18 is slid longitudinally over the rails and angle bars or fish plates, and the wedge member 25 is then 30 forced or driven in between one of the angle bars or fish plates and the yoke member 18 at the side which is spaced from the adjacent angle bar thus firmly binding together the several parts forming the joint and 35 clamping means, in the manner shown in Fig. 1 of the drawings. It will be seen that the yoke member 18 and wedge member 25 are reversible for use on either side, without making right and left hand parts and that 40 one is applied to each side of a connection or rail joint as shown in Fig. 1. The wedges are driven in toward the abutting ends of the rails at the short side or end 20 of each yoke member, this being facilitated by the 45 tapered formations by which the inclined or wedge faces 26 and the inclined or wedge surfaces 28 are provided, thus firmly holding the joints together. Extensions 24 receive the base of the rail thereon and also 50 prevent the yokes 18 from tilting or rocking when placed in position.

To prevent the wedge members 25 from becoming loose through vibration, the lateral extensions 27 thereof are provided with 55 a number of apertures 29 as heretofore described, to receive pins 30, which are driven into the nearest aperture to the face of the yoke member 18, as clearly shown in Fig. 1 of the drawings. This obviates any possibility of the wedge member becoming displaced and retains the joint intact. Thus 60 the rail ends are connected in a manner to hold the same against lateral, tilting or vertical movement without the use of screw-threaded bolts or nuts and yet in such a

manner as to permit such longitudinal movements as required in the expansion and contraction of the rails. Furthermore, an efficient electric bond is provided and likelihood of dis-association of the parts of the joints by the pounding of the rolling stock on the rails, as commonly occurs where bolts and nuts are employed, is obviated. It will also be observed that the rail ends are brought in abutting relation centrally between two ties, as indicated at 31, while the yoke members and wedges are disposed adjacent the longitudinal side faces of the ties which are remote from said abutting or confronting ends, so that the parts can be assembled very readily without interference by the ties. Furthermore, the joints provide the necessary stiffness and rigidity to obviate sagging at the joints and will in a great measure, eliminate the usual pounding from the passage of the rolling stock thereover.

Having thus described my invention, what I claim is:

1. An improved yoke for securing fish plates to a rail in making a rail joint, comprising a U-shaped yoke member having the inner face of one leg beveled and provided with a notch and the inner face of the other leg provided with a groove, and a lug extending flush with the inner face of the intermediate part on the side toward the bevel, whereby the driving of a wedge cannot tilt the yoke.

2. A rail joint for rails including angle bars adapted to engage the base flanges of the adjacent ends of rails which they embrace, a yoke member adapted to clamp the angle bars against the rails said yoke member having a transverse notch on one side and an inclined groove leading into the other side from the bottom face of the yoke, at the bright portion, said yoke having an extension at one side flush with the bottom face and adapted to engage the base of the rail when the yoke is slid over the angle bars with one side engaging an angle bar and the other side spaced therefrom, and a wedge member tapered toward one end and having a bottom lateral extension also provided with a tapered portion to enter said space and engage the notch respectively whereby to tighten the yoke in position, when driven between the spaced side of the yoke and the adjacent angle bar, and means to prevent displacement of the wedge member from its engaged position.

3. A rail joint for rails consisting of angle bars adapted to embrace the adjacent ends of the rails, said rails having apertures in their web portions and said angle bars having spaced apertures to align with each other and the apertures in the rail webs, studs having reduced portions riveted to certain apertures of the angle bars and ex-

tending through the apertures of the rail webs and into the apertures of the opposite angle bars, the flanges of the angle bars resting upon the base flanges of the rails, 5 yoke members having side portions, one side portion having a notch spaced from its bottom face and the other side having an inclined groove extending downwardly and outwardly from a plane of the bottom face 10 to permit engagement of the yoke members with the rails, said yoke members being adapted to be slid over the angle bars by accommodation of the flanges at one side in said grooves, with one side of each yoke 15 member engaging the adjacent side of the angle bar and the other side spaced from the adjacent side of the other angle bar, and wedge members insertible in said spaces and having lateral bottom extensions tapered in the direction of the wedges, and 20 increasing in width toward the tapered ends thereof to enter the notches immediately above the base flanges of the adjacent angle bars, and adjustable means to retain the wedges in position with the parts in binding 25 engagement at each side of abutting rail ends by engagement with the yoke members.

In testimony whereof I affix my signature.
PASQUALE STELLA.
